METHOD OF PURIFYING ALKALI METAL HYDROXIDES

Chester C. Brumbaugh, Painesville, Ohio, assignor to Diamond Alkali Company, Cleveland, Ohio, a corporation of Delaware

No Drawing. Application September 17, 1948,
Serial No. 49,858

6 Claims. (Cl. 23—184)

1

This invention relates to chemical manufacture and more particularly relates to a novel and efficient method of preparing alkali metal hydroxides of high purity, particularly with respect to materials of oxidizing character, such as alkali metal chlorates. This invention is especially adapted to the production of pure caustic soda.

Large volumes of caustic soda which must meet stringent specifications, especially as to content of oxidizing agents, particularly chlorates, are required for processing rayon. Caustic soda produced in the generation of chlorine by brine electrolysis is generally not available for use in rayon processes due largely to chlorate impurities, so that heretofore the much more expensive chemical and mercury cell caustic sodas have largely been used because of their purity and because of lack of a suitably inexpensive method of freeing electrolytic caustic soda from chlorates. Consequently, it has long been the desire of electrolytic caustic manufacturers to acquire a suitable method of chlorate removal and many attempts have been made without success to devise such a method. The prior art methods have either been prohibitively expensive or have not resulted in a suitable chlorate-free caustic product for rayon uses. Numerous of these prior efforts have been directed to the use of various forms of iron to destroy chlorates. Such methods are unsuccessful, however, in that there is either too much chlorate or too much iron in the final product. The other methods of chlorate removal which have been tried include the extraction of chlorate from caustic soda, extraction of caustic soda from chlorate, inhibition of the oxidative effect of chlorate, and the like, all of which were too expensive for commercial use or were insufficiently effective.

The present invention contemplates the substantially complete removal of chlorates from alkali metal hydroxides, more particularly from caustic soda solutions or from anhydrous caustic soda, either as an independent step in the manufacture of caustic soda or preferably and more conveniently in the course of obtaining caustic soda in high concentration in aqueous solution or in anhydrous condition. In general, the objects of the invention are accomplished by treating caustic soda solutions containing an undesirable quantity of chlorate ions with alkali metal sulfites, the alkali metal ion being suitably that of the alkali metal hydroxide being treated with the sulfite material. In general, the sulfite compound used may be employed in an amount equivalent to the stoichiometric amount necessary to destroy the known amount of chlorate ion present in the material, the amount of chlorate ion having been previously ascertained by analytical methods. It has been found desirable to use somewhat of an excess of the stoichiometric amount, such as a 20% excess, but those skilled in the art will appreciate that once the amount

2

of chlorate present in the alkali metal hydroxide, such as caustic soda, being treated has been determined, the specific amount of sulfite material in excess of the stoichiometric amount necessary to reduce the chlorate will become somewhat a matter of choice.

As noted above, it is contemplated that the present invention may be practiced with alkali metal hydroxide solutions and especially caustic soda solutions of more or less concentration, it being preferred to treat solutions of electrolytic caustic soda of 50% or greater concentration and particularly since those solutions have especially high concentrations of chlorate relative to chemically obtained caustic soda, the present invention has its particular applicability in the removal of chlorate from electrolytic caustic soda, which is obtained by electrolysis of sodium chloride solutions.

20 The alkali metal hydroxides, more particularly caustic soda, may suitably be treated with the sulfite compound, in the case of caustic soda, more suitably sodium sulfite, preferably at somewhat elevated temperatures, such as temperatures from 100° C. to the melting temperature of anhydrous caustic soda, it being preferred in general to incorporate the sodium sulfite as an incident of concentration procedure, whereby higher temperatures will be realized. Moreover, 25 the sodium sulfite may, if desired, be added as a solid salt or may be added as a saturated aqueous solution or in dilute aqueous solution, depending upon the point of the sodium hydroxide manufacture in which the addition is made.

30 The present invention has the particular advantage that it reduces the sodium chlorate to a tolerable limit without adding any other difficulties, or in the case of the use of sodium sulfite to caustic soda, any foreign ions to the caustic soda, particularly foreign metallic ions which are especially undesirable in this connection. A minor increase in the concentration of sulfate ion in the ultimate alkali metal will, of course, be experienced in the practice of this invention. However, higher concentrations of sulfate can much 35 more readily be tolerated, and what amounts in effect to an exchange of chlorate for sulfate, is therefore a desirable improvement in the purity of the alkali metal hydroxide.

35 The invention is particularly applicable in the reduction of the caustic soda to relatively anhydrous condition by heat exchange evaporator systems of water removal and more particularly by the falling film evaporator and separator system described in the co-pending application of R. E. 40 Hulme, Ser. No. 43,524, filed August 10, 1948. Sodium sulfite, whether solid or in solution, may suitably be added to the feed to such a concentration system at any suitable time continuously or intermittently as desired. The product as obtained will have its sodium chlorate content reduced to a tolerable limit, whereby it is available

for uses for which heretofore electrolytic caustic particularly was not available.

As pointed out above, it is in general preferred to employ an amount of sodium sulfite equal to a slight excess of the stoichiometric amount of sodium chlorate found in the caustic soda product. Thus, a typical amount of sodium sulfite to be used per ton of anhydrous caustic soda obtained will be based on sodium chlorate content, which is typical in the particular electrolytic operation referred to. An example of such operation is a caustic soda solution obtained electrolytically containing 0.166% of sodium chlorate, for which purpose it has been found useful to employ 14.1 pounds of sodium sulfite per ton of anhydrous caustic soda, whereby the chlorate content has been reduced to about 0.002%, a tolerable amount of this material for practically all industrial purposes.

The present invention is applicable to all of the alkali metal hydroxides, including lithium, potassium, sodium, rubidium, cesium, and the like. However, it will be appreciated in view of the commercial importance of the product that it has its greatest significance as applied to sodium hydroxide or caustic soda. Moreover, other sulfites than sodium sulfite, such as lithium, potassium, rubidium, and cesium, may be employed, it being particularly desirable to employ the sulfite which has a common ion with the hydroxide being treated. In accordance therewith, it will be appreciated that sodium sulfite will be preferred for treating caustic soda.

In order to inform those skilled in the art of the manner in which the present invention may preferably be practiced but in no sense to be taken as limiting upon the scope of the invention described herein, the following examples are set forth:

EXAMPLE I

Electrolytic caustic soda solution previously concentrated to a concentration of about 50% in caustic soda is passed through a falling film type evaporator, followed by a separator in which the products of the evaporator are impinged upon the wall of the separator, the entire system being maintained at a wall temperature in excess of the melting temperature of anhydrous caustic soda and as is more particularly described in the above referred to application of R. E. Hulme. Sodium sulfite aqueous solution in a ratio of 14.1 pounds of sodium sulfite per ton of caustic product from the evaporator is added to the feed of the evaporation system. The content of chlorate in the entering caustic soda solution based on anhydrous caustic is 0.166%. The content of chlorate in the material issuing from the evaporator is of the order of 0.002%.

EXAMPLE II

The procedure above was followed, varying the amount of sodium sulfite added to the feed with the following results:

Addition of sodium sulfite to electrolytic feed solution

Prod. Rate, Lb./Hr.	Na ₂ SO ₃ Add. to Feed, Lb./Hr.	Per Cent NaClO ₃ in Product
62	None	.073
63	0.4	.0018
58	0.4	.0024
60	0.21	.019
63	0.244	.017
58	0.244	.010

While there have been described various embodiments of the invention, the methods described are not intended to be understood as limiting the scope of the invention as it is realized that changes therewithin are possible and it is further intended that each element recited in any of the following claims is to be understood as referring to all equivalent elements for accomplishing substantially the same results in substantially the same or equivalent manner, it being intended to cover the invention broadly in whatever form its principle may be utilized.

What is claimed is:

1. The method of purifying an alkali metal hydroxide with respect to alkali metal chlorate, which comprises contacting a mixture of said hydroxide and said chlorate with an alkali metal sulfite at an elevated temperature.
2. The method as claimed in claim 1 in which the mixture of alkali metal hydroxide and alkali metal chlorate is contacted with sodium sulfite at an elevated temperature.
3. The method as claimed in claim 1 in which the amount of sulfite added to the alkali metal hydroxide solution is at least equal to the stoichiometric equivalent of chlorate present therein.
4. The method of removing sodium chlorate from caustic soda solutions which includes the step of contacting a caustic soda solution containing such chlorate with sodium sulfite at an elevated temperature.
5. The method of purifying sodium chlorate contaminated caustic soda with respect to said sodium chlorate which includes the step of contacting caustic soda solution of more than 50% concentration with an amount of sodium sulfite at least equal to the stoichiometric equivalent of sodium chlorate present with such caustic soda.

6. The method of dehydrating sodium chlorate contaminated caustic soda while purifying said caustic soda with respect to said sodium chlorate which includes the steps of heating such caustic soda until all of the water associated therewith has been removed, and contacting said caustic soda during the anhydrous process with sodium sulfite.
